BUILDING

Edward W. McCreary, Covina, John H. Tindall, West Covina, and Jesse C. Hood, Covina, Calif., assignors to Diamond Donut, Inc., West Covina, Calif., a corporation of California

Filed Oct. 22, 1968, Ser. No. 14,110

Term of patent 14 years

Int. Cl. D25—04
U.S. Cl. D13—1

FIGURE 1 is a front perspective view of a building showing our new design;

FIGURE 2 is a top plan view;

FIGURE 3 is a rear elevational view; and

FIGURE 4 is an end view.

The other end appears substantially similar to the end shown. Each of the end portions simulates a major segment of a doughnut, with the hole of the doughnut acting as the drive-in entrance or exit.

The dominant feature of our design resides in the portions shown in solid outline.

We claim:

The ornamental design for a building, substantially as shown and described.
